UNITED STATES PATENT OFFICE.

THOMAS MARA FELL, OF TENAFLY, NEW JERSEY, ASSIGNOR, BY MESNE ASSIGNMENTS, TO THE FELL MANUFACTURING COMPANY.

OIL-LAMP.

SPECIFICATION forming part of Letters Patent No. 392,418, dated November 6, 1888.

Application filed August 11, 1885. Serial No. 174,151. (No model.)

To all whom it may concern:

Be it known that I, THOMAS MARA FELL, of Tenafly, in the county of Bergen and State of New Jersey, have invented certain new and useful Improvements in Oil-Lamps, of which the following is a specification.

My invention relates to an improvement in lamps.

The object of my invention is to provide an improved means for feeding oil to burners by a system of siphon-tubes, and to use in connection therewith an angular or horizontal burner, whereby a better and more effective light is obtained; and a further object is to provide a globe or chimney of a peculiar form and construction to be used in connection with my angular or horizontal burners.

With these ends in view my invention consists in certain novel features of construction and combinations of parts, more fully described hereinafter, and pointed out in the claims. I attain these objects by the mechanism illustrated in the accompanying drawings, in which—

Figure 1 is a vertical section of a pendent lamp embodying my improvement, and Fig. 2 is a modification of part of my invention.

A² is the fount or oil-reservoir provided with the opening E'; B', the supporting rod or tube which slides in an outer tube, Y', which is securely attached to the plate Z', this arrangement being fitted with the usual suspension-chains, pulleys, and weights. The lower part of the supporting rod or tube B' passes through the top plate of the fount, and is brazed or otherwise fastened thereto, and if a tube the inner end is stopped by a plug, as shown.

F is a T, if for two lights, or a cross, if for four lights; but is made with three or more horizontal openings if more than two lights are to be fed. This T is secured to the lower end of the rod or pipe B', and into it are screwed the horizontal feed-pipes F', which pass through the vertical sides of the fount and are fastened thereto.

D' is a small tube screwed into F on its under side, and extends down into the chamber A³, which communicates with the fount A².

H' is the outer oil-feed tube of the burner, and J' the wick-feed tube. The tube J' is

turned in at the bottom, so as to fit the tube H', but has one or two small holes, J², for the passage of oil into the small chamber I', which is formed by the lower portion of the tube H'. The upper end of this tube J' is also flattened out and made tight by brazing to the tube H', as shown.

A⁴ is a right-angled goose-neck connection; but such angle may be varied to any degree found desirable. (See Fig. 2.) One end of this goose-neck screws on or is fitted into the upper end of the vertical tube H', the other end carrying the plate C'.

B² are air-holes around the circumference of the upper end of the goose-neck.

F² is the wick-holder, having attached thereto the usual ratchet-wheel for feeding the wick; and F³ is an extension of the lower half of the wick-holder F², the said extension being bent to conform to the shape of the goose-neck.

L² is the burner-cap, having the opening L³.

G' is a glass globe having two openings, one located at the top and the other at the side thereof, the bottom of the globe being closed. The opening in the side is adapted to fit over the burner, the globe being secured to the plate C' by means of the lip D² and screw E² in the ordinary manner. The other opening or outlet I' is vertical to the lamp. On the upper part of the globe and over the opening is a metal chimney, T', which carries a reflector-plate, K'.

I do not wish to limit myself to the use of my improved globe or chimney in connection with the peculiar form of lamp herein described, as it is evident that this improved form of globe or chimney can be manufactured and sold separately from the lamp and used in connection with any angular or horizontal burner.

The operation of this lamp is as follows: Oil being poured through the opening E' into the fount, it enters the chamber A³ and passes through the pipes D' F' H' to the wick-tube J'. The pipe D' extends down to or below the bottom of the oil-reservoir, and the opening J², being also below said bottom, permits the oil to flow from the reservoir to the wick-tube and be maintained at the same height in both

until the fount is exhausted. This system of siphon-feed permits the pipes F' to be placed centrally in the fount, thus giving a strong support to the burner and chimney. When the wick is ignited, a draft will be created by the air entering through the openings in the plate C', passing through the burner-cap and escaping through the opening I'. This draft will have the effect of drawing the flame in a curved form from a horizontal to a vertical plane. The superiority of this curved flame is that it gives most of its strongest rays of light downward from the under side of the flame, and if a reflector be used the corresponding rays of the other side of the flame will be reflected in a downward direction. A further benefit of my said improvements is in obtaining a shadowless light immediately under the burner, which is effected by the removal of the metal burner and fount from their usual positions. As a modification of my said invention, the globe G' may be extended in the form of a chimney upward, instead of using the metal top T', and the goose-neck A', which secures the angle of the burner, may be made so as to enter the lower part of the globe or chimney at an angle other than a right-angle, as shown in Fig. 2.

Having thus fully described my invention, what I claim, and desire to secure by Letters Patent of the United States, is—

1. In a lamp, the combination, with a wick-tube, an upwardly and outwardly bent goose-neck, a perforated plate secured to said goose-neck, and a burner, of a globe or chimney having an opening in its side and another opening in its top, substantially as described.

2. In a lamp, a supply-fount, a wick-tube located outside of the supply-fount, and a siphon-conduit connecting said fount and wick-tube, combined with a goose-neck in communication with and located above said wick-tube, a perforated plate upon the outer end of said goose-neck, a globe clamped to said perforated plate, and a burner carried by the perforated plate, substantially as described.

3. In a lamp, the combination, with an oil-

supply fount and a wick-tube in communication therewith, of a goose-neck, a perforated plate attached to said goose-neck, a globe clamped to said perforated plate and closed at its bottom and provided with two openings, one in its side and one in its top, said globe being provided with an upwardly-extending chimney at its top opening, and a burner extending into said side opening of the globe, substantially as described.

4. In a lamp, a supply-fount, a wick-tube located outside of the supply-fount, and a siphon-conduit connecting said wick-tube and supply-fount, in combination with an upwardly and outwardly bent goose-neck secured above the wick-tube, a downwardly-curved wick-carrier in the goose-neck, a perforated plate secured to the outer end of the goose-neck, and a burner extending from the goose-neck through the plate, substantially as described.

5. In combination with a burner, a globe having a closed bottom and an opening at its side to receive the burner, and another opening at its top, whereby a draft is created which draws the flame in a curved form upward from a substantially horizontal plane, for the purpose specified.

6. The combination, with a burner and a perforated plate, of a globe or chimney carried by the plate, having a closed bottom and an opening in its side to receive the burner and another opening in its top, and an upwardly-extending chimney carried by the globe and surrounding the top opening in the same, substantially as described.

7. The herein-described lamp, consisting, essentially, of an oil-supply fount, an upright tube located therein, a horizontal tube connected with said upright tube and extending to the exterior of the fount, an oil-feed tube upon the outer end of said horizontal tube, a wick-tube, an upwardly and outwardly bent goose-neck above said wick-tube, a wick-carrier, a perforated plate, a globe clamped to said plate, and a burner, as specified.

THOMAS MARA FELL.
